UNITED STATES PATENT OFFICE.

CHARLES E. SKELTON, OF EAST ONONDAGA, NEW YORK.

TOOL POST.

Application filed July 7, 1922. Serial No. 573,337.

To all whom it may concern:

Be it known that I, CHARLES E. SKELTON, a citizen of the United States, and a resident of East Onondaga, in the county of 5 Onondaga and State of New York, have invented a certain new and useful Tool Post, of which the following is a specification.

This invention has for its object a particularly simple, efficient and durable construction of tool post or similar article by 10 which the tool holder can be adjusted without interfering with the clamping means holding the tool post to a carriage or other support, and hence the proper cutting angle 15 preserved and by which in boring operations the tool can be shifted to change the cutting edge in order to have a proper clearance without changing the tool holder for vertical adjustment or angular position.

20 The invention consists in the novel features and in the combinations and constructions hereinafter set forth and claimed.

In describing this invention, reference is had to the accompanying drawings in which 25 like characters designate corresponding parts in all the views.

Figure 1 is a vertical sectional view of the tool post, the contiguous part of the carriage or support being shown in section.

30 Figure 2 is an elevation of the tool post, the carriage or support being shown in section.

Figure 3 is an elevation of the tool post partly broken away.

35 Figure 4 is a plan view thereof.

This tool post comprises generally, a post proper having means for clamping it to a carriage or other support, a tool holding body adjustable along the post proper, 40 and means independent of the clamping means for adjusting the tool holding body.

It also preferably includes means independent of the clamping and adjusting means for holding the tool holding body in 45 its adjusted position.

1 designates the post proper, it being here shown as a block cylindrical in general form.

The means for clamping the post proper 1 to a support as a cross feed carriage 2, as 50 here shown, includes a screw 3 extending axially of the post proper 1 and threading at its lower end into a T-shaped nut 4 arranged in the T slot 5 of the carriage 2, the screw having threads 6 at its lower end threading

into the nut 4 and also having threads 7 55 preferably of a different pitch at its upper end threading into the post proper 1.

The screw is accessible from the top face of the base 1 and as here shown, is formed with an angular socket 8 for receiving a 60 suitable wrench.

Preferably, the threads 6 at the lower end of the screw 6 are of a coarser pitch than the threads 7 at the upper end of the screw 3.

The threads 6, 7 are both either right or 65 left hand threads, preferably, right hand. Hence, upon turning of the screw 3, the nut 4 is pulled upwardly faster than the post 1 is shifted downwardly and owing to the different pitch of the threads, the post is held 70 in its clamped position without the use of lock nuts and similar devices.

9 designates the tool holding body which is sleeved on the post proper 1 and adjustable vertically thereon, it being here shown 75 as square in cross section and having a cylindrical passage fitting the cylindrical post proper 1.

The tool holding body is also formed with channels 11, 12 on opposite sides thereof for receiving the tool as 13 or 14 and with set screws 15 extending into the channels preferably from the top side thereof for engaging the tools.

The means for adjusting the tool holding 85 body 9 vertically includes means operable from the top side of the tool post and coacting with the post proper and with the body 9, such means extending lengthwise of the post and the body and between surfaces of 90 the post and the body.

In the illustrated embodiment of my invention, this means comprises a screw held from endwise movement by the post proper 1 and engaging threads on the body.

As best seen in Figs. 1 and 4, the post proper is formed with a recess 16 extending lengthwise thereof and opening through its peripheral face, the recess being substantially semicylindrical, and the body 9 is 100 formed with a complementary semicylindrical recess 17 formed with internal threads. Also, the post 1 is formed with bearings which are axial extensions of the recess 16 and of less diameter than the recess 16, these 105 bearings opening through the peripheral face of the post 1 and the upper bearing also opening through the top face of the post 1.

18 is the adjusting screw, it being located in the recesses 16, 17 and meshing with the threads of the recess 17 and having axles 19 and 20 at its upper and lower ends located 5 or lying in the bearings or extensions of the recess 16. The screw 17 at the bases of the axles thrusts in opposite directions against the upper and lower walls of the recess 16 and is held thereby from endwise movement.

10 The upper axle 19 is provided with a suitable socket 21 in its upper end for receiving a suitable wrench for turning the screw.

Obviously, as the screw is turned in one 15 direction or the other, the tool holding body 9 will be elevated or lowered without disturbing the screw 3 which clamps the tool post 1 to the cross feed carriage.

The means for firmly holding the tool 20 holding body 9 in its adjusted position is also operable from the top side of the tool post and comprises a wedge movable between opposing surfaces of the tool post proper 1 and the body 9 and a screw for shifting the 25 wedge. 22 is the wedge which is here illustrated as slidable in a recess 23 formed in one side of the tool post proper 1 and opening through the peripheral face thereof, the recess having an inclined bottom 23^a opposed to the opposing inner face of the body 9 and the wedge also having an inclined face coacting with this inclined bottom.

The wedge also has a cylindrical face on 35 its outer side coacting with the inner cylindrical face of the body 9.

24 is the screw which extends through a suitable passage extending vertically of the post proper 1 and into the upper end of the 40 passage 23. The screw 24 is provided with a head 25 which holds the screw from endwise movement downwardly.

The screw threads into the wedge 22. The 45 head 25 is provided with a suitable socket for receiving a wrench by means of which the screw is turned. Obviously, upon turning of the screw 24 in one direction or the other, the wedge will be moved downwardly or upwardly to loosen or tighten the wedge 50 against the tool holding body 9.

The heads of the screws 3, 19 and 24 are flush or nearly so with the top of the post. Also, the heads of the tool holding screws 55 15 are flush with the top faces of the channel 11, 12.

The tool 13 is a cutter used in external 60 turning operations, and obviously, by reason of the fact that the tool holding body can be raised and lowered without shifting the tool post proper, a change of position of the tool is accomplished without varying the cutting angle.

The tool 14 is a boring bar and in boring 65 operations, it is necessary to change the position of the cutting edge in order to have

the proper clearance. This may be accomplished without changing the setting of the tool for vertical adjustment or angular position.

Furthermore, owing to the fact that the 70 tool post has no projections and also as there are no projections over the side of the boring bar the operator has almost unobstructed view of the work when boring.

What I claim is:

1. A tool post comprising a post proper having means for clamping it to a support, a tool holding body adjustable vertically of the post proper, the post proper being formed with a lengthwise recess opening through the face opposed to the body, the recess being formed with an upright inclined bottom facing the inner face of the body, a wedge movable vertically in the recess and engaging the bottom of the recess and the opposing inner face of the body, and a screw extending into the recess from the top of the post proper, the screw threading into the wedge, substantially as and for the purpose specified.

2. A tool post having a screw extending vertically thereof having threads at its lower end for threading into a clamping nut on the support for the post, and threads at its upper end of different pitch threading into the post, substantially as and for the purpose set forth.

3. A tool post comprising a post proper having means extending vertically therethrough for clamping the post to a support and operable from the top of the post, a tool holding body sleeved on the post proper, and means operable independently of the clamping means for adjusting the body vertically of the tool post proper, the adjusting means being operable from the top of the tool post, substantially as and for the purpose described.

4. A tool post comprising a post proper having means extending vertically therethrough for clamping the post to a support, and operable from the top of the post, a tool holding body sleeved on the post proper, means operable independently of the clamping means for adjusting the body vertically of the tool post proper, the adjusting means being operable from the top of the tool post, and means operable from the top of the post independently of the clamping and the adjusting means for holding the body in its 120 adjusted position, substantially as and for the purpose specified.

5. A tool post comprising a post proper and a screw extending vertically through the post proper and operable from the top thereof for clamping the post to a support, a tool holding body sleeved on the post proper, and means for adjusting the body vertically of the post proper including a screw extending vertically of the post proper and the 130

body and operable from the top of the post, substantially as and for the purpose set forth.

6. A tool post comprising a post proper and a screw extending vertically through the post proper and operable from the top thereof for clamping the post to a support, a tool holding body sleeved on the post proper, means for adjusting the body vertically of the post proper including a screw extending vertically of the post proper and the body

and operable from the top of the post, and means including a screw extending vertically of the post proper and the body for holding the body in its adjusted position, substantially as and for the purpose described.

In testimony whereof, I have hereunto signed my name, at Syracuse, in the county of Onondaga and State of New York, this 25th day of May, 1922.

CHARLES E. SKELTON.
